TAPE CASSETTE DECK

Lawrence Levow, Huntington, N.Y., assignor to Harman-Kardon, Incorporated, Plainview, N.Y., a corporation of Delaware

Filed Jan. 8, 1969, Ser. No. 15,252

Term of patent 14 years

Int. Cl. D14—01

U.S. Cl. D26—14

The figure is a front, top and right side perspective view of a tape cassette deck showing my new design.

The left side is the same in appearance as the illustrated right side.

The back and bottom are essentially plain and unornamented.

I claim:

The ornamental design for a tape cassette deck, as shown and described.
